UNITED STATES PATENT OFFICE.

ROBERT M. KING, OF WAUNETA, NEBRASKA.

AUTOMATIC GATE.

1,274,278.

Specification of Letters Patent. Patented July 30, 1918.

Application filed August 25, 1917. Serial No. 188,103.

To all whom it may concern:

Be it known that I, ROBERT M. KING, a citizen of the United States, residing at Wauneta, in the county of Chase and State 5 of Nebraska, have invented new and useful Improvements in Automatic Gates, of which the following is a specification.

This invention relates to gates and comprehends the provision of a novel construction 10 of means for automatically opening and closing the gates, said means being actuated to open the gates by the approach of a vehicle at the gate entrance.

In carrying out my invention I provide 15 means by which the gates can be automatically operated from either side, together with means for locking the gates in their normal closed position, with a view of preventing cattle or other live stock from forcing 20 the gates open by bearing against the latter.

The nature and advantages of the invention will be better understood when the following detail description is read in connection 25 with the accompanying drawings, the invention residing in the construction, combination and arrangement of parts as claimed.

In the drawings forming part of this 30 specification like numerals of reference indicate similar parts in the several views and wherein:—

Figure 1 is a perspective view showing the gates closed and the vehicle actuated elements in normal position.

Fig. 2 is a plan view of the gate operating mechanism, showing the gates by dotted lines in opened position.

Fig. 3 is a sectional view taken on line 40 3—3 of Fig. 2.

Fig. 4 is an enlarged detail view of the locking mechanism.

Referring more particularly to the drawings in detail A and B respectively indicate 45 a pair of swingingly mounted gates, the mechanism for actuating the gates being disposed beneath the ground or surface, with the exception of the vehicle actuated elements which project a slight distance 50 above the ground as clearly illustrated in Fig. 1. The mechanism is arranged within a housing preferably of the design shown, which is in the form of a cross, including a longitudinally disposed branch 10 and a 55 transversely disposed branch 11. Each of the respective branches comprises a bottom

12 and vertically disposed spaced parallel walls 13, across which is removably secured a top 14. Rising from the extremities of the transversely disposed branch 11 are uprights 15 which are connected by means of a cross piece 16 defining the gate opening or entrance, the gates A and B being swingingly mounted within the opening defined by these parts, and normally closed. The 60 gate posts 17 are mounted for partial rotation between the cross piece 16 and the top 14 of the transversely disposed branch of the housing as illustrated.

Rising from the base of the housing, and 70 at the central point of intersection between the branches 10 and 11, is a pivoted bolt 18 upon which is pivotally mounted a pair of triangular shaped plates 19 and 20 respectively the said plates being disposed in 75 superimposed relation, and held spaced through the instrumentality of a sleeve 21 which is fitted upon the pivot bolt 18 and interposed between the respective plates. The plates 18 and 20 are pivotally mounted 80 at a point approximately midway along one of their straight edges, while connected with each of the two most remote corners of each plate is a rod 22, the rods of each plate extending in the direction of one of the gate 85 posts 17 and disposed in parallelism.

The gate posts 17 project below the top 14 of the housing, the projecting extremity of each having fixed thereon a cog wheel 23, which is horizontally disposed, and about 90 which is trained a chain 24, the terminals of the chain being connected with the adjacent extremities of the rods 22. The plates 19 and 20 are mounted to swing about their pivot in relatively reverse directions, and 95 the manner of manipulating the plates will be hereinafter fully described. With this fact borne in mind however it will be noted that when the plates are thus moved about their pivot the rods 22 for each gate are reciprocated in relatively reverse directions, while the corresponding rods of the respective pairs of rods move toward and away from each other, an operation which results in the swinging of both gates in a common 100 direction to an opened position. It is of course understood that when the rods 22 are reciprocated, or actuated in the manner described, the chains 24 are drawn about the cog wheels 23, rotating the latter, which of 105 course swing the gates in the manner stated.

Arranged to reciprocate in the longitudi-

nal branch 10 of the housing, and at opposite sides of the transverse branch 11, are operating rods 25, the innermost extremity of each rod being provided with branches 26. The branches 26 of the respective rods have their adjacent extremities overlapped, one and corresponding branches of the respective rods being connected to the plate 19 at a point directly opposite the pivot 27. Therefor, while the remaining and corresponding branches of said rods 25 are connected to the plate 20 at the same location. By reason of this fact the plates 19 and 20 respectively are simultaneously swung upon their pivot, so that both the gates A and B are moved in unison to either their opened or closed position. A lever 27 is pivotally mounted adjacent the outer extremity of each rod 25, and is also pivotally connected with said outer extremity of said rods, the levers 27 projecting above the ground or surface in the path of movement of a vehicle approaching the gates, so that when the lever 27 of one of the rods 25 is moved upon its pivot in the direction of the gates, both of the rods 25 will be moved in unison in a direction to impart movement to the plates 19 and 20 in relatively reverse directions, whereupon the gates A and B will be simultaneously swung outwardly to an open position. Pivotally connected with the rod 25 at the point of juncture of the rod with its branches 26, is a second lever 29 which also projects a slight distance above the ground or surface to operate in unison with the lever 27. The levers 27 and 29 for this purpose are connected together through the instrumentality of a bar 30.

In practice, the vehicle passes over the levers 27 and 29 when approaching the gate entrance, and as the axle of the vehicle is brought into engagement with the lever 27 the latter is moved upon its pivot in the direction of the gates A and B, whereupon the gates are swung in the same direction to an open position in the manner hereinabove described. The axle of the vehicle then engages the bar 30 moving along the latter, with a view of maintaining the gate in an open position, it being manifest that as long as the bar is depressed the gates are maintained in an open position. Before the front axle moves beyond the lever 29, or in other words off the bar 30, the rear axle has been brought into engagement with said bar to hold the latter depressed and the gates open, thus affording ample opportunity for the vehicle to pass through the gate entrance before the gates are automatically closed. For this purpose a coil spring 31 encircles each rod 25, the spring having one end bearing against a plate 32 fixed between the side walls 13, while the opposite end of the spring bears against a nut 33 carried by the bar. The construction and arrangement of parts

at opposite sides of the gates considering the latter in their normal closed position, is identically the same, and consequently the operation of the parts in the opening of the gates is the same, irrespective of which side 70 the gates are opened. The top 14 for the housing is of course provided with elongated slots 34 to permit of the proper movement of the levers 27 and 29.

With a view of locking the gates in their 75 normal closed position, I provide a lever 35 which is pivotally mounted upon the lever 27, and provided with a right angular extension 36. The right angular extension is pivotally connected with one extremity of a locking dog 37, through the instrumentality 80 of a link 38, the locking dog 37 being pivotally mounted upon the lever 27 adjacent the lower extremity of the latter. A spring 39 is interposed between the levers 27 and 35 85 to normally maintain the latter separated, and the locking dog arranged adjacent the shoulder 40 formed on a fixed element 41. With these parts in their normal position, it is obvious that the gates A and B cannot be 90 swung to an opened position, thus preventing cattle or the like from entering the gates by bearing against the latter. A slight movement of the gates in an effort to open them will cause the dog 37 to engage the 95 shoulder 40. However when a vehicle approaches the gate, the lever 35 being disposed in advance of the lever 27, is first engaged by the axle of the vehicle, and moved toward the lever 27 against the action of the 100 spring 39. During this movement of the lever 35 movement is imparted to the dog 37 in a direction whereby the actuating extremity of the dog is moved upwardly above the shoulder 40. Of course, during the continued movement of the vehicle, the axle 105 thereof is brought into engagement with the lever 27, and the latter and lever 35 are moved as a unit in the direction of the gates, to swing the latter to an opened position in 110 the manner hereinabove fully described.

While it is believed that from the foregoing description the nature and advantages of the invention will be readily apparent, I desire to have it understood that what is herein shown and described constitutes one embodiment of the invention, which I do not consider restrictive, and that such changes in the construction and arrangement of parts may be resorted to when desired as fall within the scope of what is claimed. 115 120

What is claimed is:-

1. The combination with a pair of swinging gates, of a mechanism disposed beneath the ground for moving said gates to an open position, said mechanism including a vehicle actuated element projecting above the ground, means for locking said gates in closed position and said means including a vehicle actuated element pivotally mounted 130

upon the afore-mentioned element and yieldable means for normally holding the element of the locking mechanism in advance of the first mentioned element to be initially engaged by the vehicle to effect a release of said gates.

2. The combination with a pair of swinging gates, of a mechanism disposed beneath the ground for moving said gates to an open position, said mechanism including a vehicle actuated element projecting above the ground, means for locking said gates in position, and including a fixed element, a movable element pivoted upon the vehicle actuated element, a locking dog carried by said movable element to engage the fixed element, and means for holding the movable element in advance of the vehicle actuated element to be initially engaged by the vehicle to effect a release of the gates.

3. The combination with a pair of swinging gates, of a mechanism for controlling the movement of said gates, and including a pair of spaced vertically disposed elements pivoted at a point between their ends, a rod connecting the lower extremities of said elements, a bar connecting the upper extremities of said elements, a connection between said rod and gates whereby the latter are moved to open position upon moving of

said rod in one direction, one of said elements being disposed in the path of travel of the vehicle to be engaged by the latter whereby said elements and rod are actuated to open said gates, a spring encircling said rod and operable to automatically return the gates to their normal positions subsequent to the passing of the vehicle through the gate-way, and means for locking said gates in closed positions.

4. The combination with a pair of gate posts mounted for partial rotation and a gate carried by each post, of a pair of oppositely disposed triangular shaped plates, said plates having their straight edge disposed in spaced superimposed relation, a pivot passed through both of said plates adjacent the straight edges thereof, rods projecting from the remote corners of said plates in a direction of said gate-post, a cog-wheel carried by each post, a chain trained over each of said wheels and having its ends connected with the adjacent extremities of said rods whereby the gates are moved to an open position upon the reverse movement of said plates, means for actuating said plates and including a vehicle actuated element.

In testimony whereof I affix my signature.
ROBERT M. KING.
